UNITED STATES PATENT OFFICE.

ROBERT MEMMINGER, OF NUEREMBERG, GERMANY.

FERMENTING-BUNG.

1,129,885.

Specification of Letters Patent.

Patented Mar. 2, 1915.

Application filed March 27, 1914. Serial No. 827,767.

To all whom it may concern:

Be it known that I, ROBERT MEMMINGER, a citizen of the German Empire, residing at Nuremberg, Bavaria, Germany, have invented certain new and useful Improvements in Fermenting-Bungs, of which the following is a specification.

My invention relates to improvements in fermenting-bungs, as used on beer barrels and the like and of the class where the gases to be discharged escape through a weighted hollow tube or rod, slidably provided in a case and carrying a discharge-valve which opens by meeting with a detent or stop, provided within the road of the rod of the said valve and the objects of my invention are, first, to provide for a sharper transmission of fluctuating pressures upon the valve-rod; second, to dispense with the use of the weighing-down springs heretofore required; and, third, to permit of a more accurate adjustment of the apparatus and at the same time of a certain relief to the same.

I attain my objects by the construction and arrangement of parts, as hereinafter set forth and described and as illustrated on the drawing herewith in which—

Figure 1 is a partial front elevation of and a partial longitudinal section through my improved device and Fig. 2 is substantially a transverse section on the line A—B of Fig. 1.

My apparatus comprises a case 1 closed at the bottom by a hollow bottom-piece 2 and on top by a cover 4, the said bottom-piece having a coupling stud 3 or the like for connection with the barrel. It contains an adjustable tube or hollow rod 7 having attached thereto a permanent weight 8 and an expansible hollow body 5, Fig. 1 showing by way of example an india-rubber bag, communicating with the hollow rod 7. The said body 5 is in turn communicating by a suitable passage, as a hollow screw 6, with the bottom-piece 2, the fermentation gases coming from the barrel through the coupling stud 3 and traveling into the bottom-piece 2 of the apparatus whence they get through the passage 6 into the expansible body 5 which they inflate, a portion of the gases entering the tube 7 held down by the aforesaid permanent weight 8. The upper end of the said tube or hollow rod 7 has a head-piece 9 containing a discharge-valve

10, the valve-rod of the same being passed 55 through the top of the said head-piece. This valve-rod I prefer to provide on top with an adjustable flanged piece 11 against which a pair of swinging levers 12, 12', seated on top of the head-piece 9, may bear 60 and press the valve-cone against its seat. At a suitable, that is at such relative distance above the top-end of the valve-rod as is within correspondence of its stroke and within the road of its said top-end, a stop 65 or detent 13 is provided which, when the valve is raised by the gas in the body 5 and the valve-rod strikes against the said detent, overcoming the action of the weights, causes an opening of the discharge-valve. 70

To permit the adjustment of the apparatus for the several pressures under which the gases are to be blown off I provide a regulator made up of a gear of connecting rods 14, 15, the gear rod 14 engaging the 75 tube or hollow rod 7. The rod-gear may be actuated by any suitable device, but I prefer a lever arrangement as shown on the drawing which comprises a double-armed lever swinging on a fixed point and weight- 80 ed. The double lever I prefer to be formed by bending it round, thus, that there are two arms 17, 17' of unequal lengths, the shorter one being attached to the pivot 18, secured in a fixed place, as the frame of the 85 apparatus and at the same time, by means of a member 16, to the rod-gear 15 aforesaid, while the other arm 17' carries a sliding weight 19. This weight I prefer to be adjustable on the said arm right or 90 left to the swinging point of the shorter arm 17, as indicated by — and + on the drawing, and, accordingly, although the apparatus is controlled by the permanent weight 8 hereinabove mentioned, it may at 95 pleasure be either additionally charged or it may be relieved and thus made to blow under either a stronger or weaker pressure than that which would be permitted by the action of the weight 8. The height of the 100 stroke of the rods remaining uniform throughout, an adjustment of the stop or detent 13 is not required.

It will be understood from the foregoing and by an examination of the drawing that 105 the principal features distinguishing my invention from the types known heretofore, especially those where the hollow rod is

passed through a piston or through a reversible india-rubber bag, are, first, the employment of a hollow body, closed in itself, expansible and adapted to receive and partially hold any gases conducted into the apparatus and, second, by a special adjusting weight, in addition to a permanent weight, and so adjustable that the apparatus may, as aforesaid, be additionally charged or at pleasure relieved.

It is clear that while my improved device is chiefly intended for employment on beer barrels, it may be used with advantage wherever accumulating gases may be drawn off and it is further evident that various changes may be made in the details of construction without departing from the general spirit of my invention.

I claim:

- 20 1. In an apparatus of the class described the combination with a weighted sliding tube carrying a discharge valve, of a closed expansible body communicating with the said sliding tube.
- 25 2. In an apparatus of the class described the combination with a weighted sliding tube carrying a discharge-valve, of an india-rubber bag communicating with the said sliding tube.
- 30 3. In an apparatus of the class described the combination of a sliding tube, a weight attached thereto, means for the admission of gases, a closed expansible body communicating with the said tube and admission means, and a discharge-valve on top of the said tube.
- 35 4. In an apparatus of the class described, having a hollow, slidable rod or tube adapted to receive gases conducted into the same and a discharge-valve for the said gases attached to the said rod or tube, the combination therewith of a permanent weight controlling the said rod and of an adjust-

able weight adapted to charge additionally or reduce the action of the said permanent weight.

5. In an apparatus of the class described the combination of a sliding tube, a weight attached thereto, means for the admission of gases, an india-rubber bag communicating with the said tube and admission means and a discharge-valve on top of the said tube.

6. In an apparatus of the class described, having a hollow slidable rod, adapted to receive gases conducted into the same and a discharge-valve for the said gases attached to the said rod, the combination therewith of a permanent weight attached to the said rod, a double-armed lever turning about a fixed point, an intermediary gear between the said lever and hollow rod and a weight adjustable on the said lever.

7. In an apparatus of the class described having a hollow slidable rod adapted to receive gases conducted into the same and a discharge-valve for the said gases attached to the said rod, the combination therewith of a permanent weight attached to the said rod, a lever, an intermediary gear between the said lever and hollow rod, the said lever being bent round, forming two arms of unequal lengths, the shorter of the said arms being turnable about a fixed point and adapted to operate the said gear, and a weight adjustably attached to the longer of the said arms and changeable in position to the aforesaid fixed point, substantially as described and for the purposes set forth.

In testimony whereof I have hereunto affixed my signature in the presence of two witnesses.

ROBERT MEMMINGER.
